United States Patent Office.

ROBERT A. GOODYEAR, OF BINGHAMTON, NEW YORK.

Letters Patent No. 99,429, dated February 1, 1870.

VENTILATOR.

The Schedule referred to in these Letters Patent and making part of the same.

To all whom it may concern:

Be it known that I, ROBERT A. GOODYEAR, of Binghamton, in the county of Broome, and State of New York, have invented an Improvement in Means for Ventilating; and the following is declared to be a correct description of the same.

The object of this invention is to ventilate by an ordinary window, without exposing the occupants of the room to a draught of air.

If a window is raised at the bottom, or lowered at the top, a direct current of air passes above or below the sash into the room, and usually, if the bottom sash is raised, a cold current of air passes in below the sash, and there is an outward ventilation between the top and bottom sash. In all these cases, the air that enters the room is very likely to be detrimental to health, or disagreeable in some portions of the apartment.

My invention is made with reference to admitting air between the upper and lower sashes of a window, and consists in a movable sash-strip provided with elastic material to make a tight joint with the lower sash, so that when the sash is raised, and said strip inserted in the window-frame, and the sash closed down upon the same, the parts around the bottom of the sash will be tight, but the lower sash will be kept up, leaving a space between the meeting rails, through which a ventilating current of air may pass. If that current is an outward one, the heated air will pass off from near the middle of the window, and if that current of air is inward, the same will be deflected upward between the two sashes, and commingle with the warmer

atmosphere in the upper part of the room, producing an agreeable supply of fresh air.

In the drawing, I have represented in a vertical section, fig. 1, the lower and central portions of window-sashes with the sash-strip *a*, below the lower sash *b*, and setting within the stop-bead *c*, so that the meeting rail *d* will be raised above the meeting rail *e*, of the upper sash, and thereby allow the aforesaid space for ventilation.

The strip of rubber *i*, or other elastic material, serves to make a tight joint between the strip *a*, and bottom of the sash *b*.

If the strip of material be in one piece, the ends should be rounded slightly, so that it may be dropped in between the stop-beads and parting-strips, by entering one end, and then the other, while in an inclined position, or said strip may be made in two parts, hinged as shown in the sectional plan, fig. 2, so that the sash-strip may be partially folded to enter the ends between the stop-beads and parting-strips.

The vertical joint may be rendered tight by the strip of rubber *o*, secured in one portion of the strip *a*.

I claim, as my invention—

The sash-strip *a*, and elastic material, at *i*, applied in the manner specified, to allow ventilation to take place between the upper and lower sashes, as set forth.

Dated this 28th day of December, A. D. 1869.

R. A. GOODYEAR.
